CLAIM

The ornamental design for an endotracheal tube holder, as shown and described.

DESCRIPTION

FIG. 1 is a front elevational view of an endotracheal tube holder, showing my new design;

FIG. 2 is a front elevational view of an alternate embodiment of the endotracheal tube;

FIG. 3 is a side elevational view of FIGS. 1 and 2;

FIG. 4 is a rear elevational view of FIG. 1;

FIG. 5 is a rear elevational view of FIG. 2; and,

FIG. 6 is a side elevational view of FIGS. 1 and 2, opposite that shown in FIG. 3.

FIG. 1

FIG. 2

FIG. 4

FIG. 5

FIG. 3

FIG. 6
